UNITED STATES PATENT OFFICE.

JOHN S. STRICKLAND AND CHARLES H. BEACH, OF TACOMA, WASHINGTON.

AUTOMATIC CAR-STOPPING DEVICE.

1,079,451.

Specification of Letters Patent.

Patented Nov. 25, 1913.

Application filed June 26, 1909. Serial No. 504,546.

To all whom it may concern:

Be it known that we, JOHN S. STRICKLAND and CHARLES H. BEACH, citizens of the United States of America, residing at Tacoma, in the county of Pierce and State of Washington, have invented certain new and useful Improvements in Automatic Car-Stopping Devices, of which the following is a specification, reference being had therein to the accompanying drawing.

This invention relates to devices for automatically stopping cars and has special reference to electric street and interurban cars.

The object of our invention is to provide a device, to be used in connection with the automatic electric signal lights at present in use, which will prevent a car from entering a block against a signal, when the block is occupied by an approaching car; which automatically applies the brakes to the car without any action on the part of the motorman; which cuts out the motorman's brake-controlling apparatus; and in which it is necessary for the motorman to make a special movement in order to release the brakes of his car if they have been applied by this emergency apparatus.

We attain these and other objects by the devices and mechanisms illustrated in the accompanying drawings, in which—

Figure 1 is a diagrammatic view of the two ends of a block equipped with a signal light and with our automatic stopping device; Fig. 2 is a partial section of the upper end of a trolley pole; Fig. 3 is a vertical longitudinal section of the magnetic contact device with its cover removed; Fig. 4 is a plan thereof; Fig. 5 is an elevation of the interior of the front end of a car equipped with our automatic stopping device; and Fig. 6 is a vertical section of the magnetic brake controlling device.

Similar numerals of reference refer to similar parts throughout the several views.

This invention is intended to be used in connection with an electric signal apparatus such as is now commonly used on single track electric trolley lines.

The invention is controlled by the automatic switches of the signal apparatus to which it is connected, taking its actuating current directly from the signal apparatus, said signal apparatus being indicated in Fig. 1 but not otherwise illustrated.

Referring to Fig. 1, the system of block

signals therein illustrated is one in which the passing of the trolley pole of a car over a controlling switch, throws the switch and energizes one set of wires which indicate a white light in the adjacent signal and a red light in the signal at the other ends of the block. It is immaterial, so far as this invention is concerned, how the said switch is thrown, the only essential being that the signal circuit is energized at the distant end of the block.

In the drawing, the trolley wire 1 is shown broken so as to indicate the two ends of the block and a car has just entered the block from the right, as indicated by the trolley pole 2. This has thrown the switch 3, at the right-hand end of the block, so as to energize the wire 4, leading to the white lamp 5 in the adjacent signal, and from thence to the other end of the block. Now the present practice has always been to connect this wire 4 directly to the red lamp 6 at the other end of the block, but we lead it first beyond the end of the block to the magnet 7 of the contact device and thence to the red lamp 6 and to the return or ground wire. A similar wire 14 leads from the similar left-hand switch 13, through the left white lamp 15 to the magnet of the right-hand contact device 17, and then through the right red lamp 16 to the ground. This latter circuit is energized when a car, having trolley pole 12, enters the block from the left. The first above circuit is indicated in full lines in the drawings while the latter circuit is indicated in dotted lines therein.

The magnetic contact device comprises an electromagnet 7, energized as above described, and mounted on a wooden base 8, to which the guy wires 9 are secured. On the other end of the base 8 are secured the two metal brackets or arms 10 to which the trolley wire 1 is fastened, thus supporting the base 8 by the action of the trolley wire 1 and the guy wires. A curved contact strip 11 is secured to the outer edge of the wooden carrier 18 which is supported and guided by the side rods 19, on each side of the magnet 7, sliding in suitable supports on the base 8. The strip 11 is constantly energized by a wire 20 connecting it to the arms 10 and thus to the trolley wire 1. The compound rod, formed of the iron rod 21 and the brass rod 22, placed end to end with the brass part within the magnet when it is not energized while the iron part is drawn there-

into when the magnet is energized, is secured to the carrier 18 and passes through the center of the electromagnet 7. The action of the magnet, as above described, 5 is counteracted by the action of a spring 23 which joins the end of the rod 21 to a portion of the supporting frame. The parts are so arranged that when the magnet 7 is energized the contact strip 11 is forced 10 outward from the base 8, by the attraction exerted on the iron rod 21, into a position in which it will be touched by the trolley pole of any car which attempts to pass it. A cover 37 is fitted on the contact device to 15 protect it from exposure to the elements.

Referring now principally to Figs. 2 and 5, it will be observed that the trolley pole 12 has an insulated metallic ring 24 around its upper end in such position thereon that it 20 will be engaged by the contact strip 11 as the pole passes it if the magnet 7 is energized. This insulated ring 24 is connected by an insulated wire, indicated at 25, to the brake-controlling device in the motorman's 25 vestibule.

Referring now to Figs. 5 and 6, the brake-controlling device is mounted in the pipe 26 which leads from the brake valve 27, by means of which the motorman controls the 30 car. The air is supplied to the brake valve 27 through the central pipe 28. The emergency three-way valve 29 is located at the junction of the air pipe 26 with the bypass pipe 30 which joins the pipes 26 and 28. 35 This valve 29 is adapted, normally, to close the pipe 30 but to allow-free passage in the brake pipe 26; but when turned by the emergency apparatus, it opens the pipe 30, thus connecting the pipe 28 to the lower 40 part of the pipe 26, and closing off the upper part of said pipe 26 and the brake valve 27. It is evident then that when in its normal position (Fig. 6) the air passes up the pipe 28 to the brake valve 27 and from 45 thence it passes down the pipe 26 through the valve 29 to the brakes; and that when it is turned at right-angles to its normal position, the air passes up pipe 28, through connecting pipe 30, through valve 29 and the 50 lower part of the pipe 26 to the brakes. The valve 29 is controlled by the handle 31, connected by the link 32 to the iron bar or plunger 33 of the electromagnet 34. The

said parts 31, 32 and 33 being arranged so that when the valve 29 is in its normal 55 position they are in position to be acted on through the agency of the magnet 34; and that when it is energized the bar 33 will be drawn down thus turning the valve 29 into the emergency position. The action of the 60 magnet 34 is only momentary but is sufficiently long to turn the valve 29, and when the valve has been thus turned it remains in this position until the motorman reaches down to the handle 31 and turns it back to 65 its normal position. The magnet 34 and valve 29 and the operating parts connected thereto are all inclosed in a case 35 which has a slot 36 in one side through which the end of the handle 31 projects. The wire 70 25 from the insulated ring 24 on the trolley pole 12 leads directly to the electromagnet 34 and from thence to the ground through the controller box or in any desired manner.

Having described our invention, what we 75 claim is:

In an automatic car stopping device, the combination with an electric signal circuit, and a car propelling circuit, of a magnetically operated contact device, the magnet 80 portion of said contact device being within said signal circuit and controlled thereby and the contact portion adapted to be moved into the path of a car, that portion of the contact device which is adapted to be moved 85 into the path of the car being electrically connected with the car propelling current, an insulated contact device mounted on said car and adapted to touch said contact device as it moves therewith, when said contact is 90 in said path, a train controlling device, and electromagnetic means in electrical connection with the contact device on the car and within the car propelling circuit when contact is made with the magnetically operated contact device, said electromagnetic 95 means adapted to operate the train controlling device.

In testimony whereof we affix our signatures in presence of two witnesses.

JOHN S. STRICKLAND.
CHARLES H. BEACH.
